(57) **CLAIM**

The ornamental design for a temperature control component, as shown and described.

DESCRIPTION

FIG. 1 is a side perspective view of a thermal control component showing our claimed design.

FIG. 2 is a first side view of our claimed design.

FIG. 3 is a second side view of our claimed design.

FIG. 4 is a third side view of our claimed design.

FIG. 5 is a fourth side view of our claimed design.

FIG. 6 is a top view of our claimed design; and,

FIG. 7 is a bottom view of our claimed design.

The broken lines in the figures show portions of the thermal control component that form no part of the claimed design.
